UNITED STATES PATENT OFFICE.

URBAN S. ALZ, OF GARDENVILLE, MARYLAND, ASSIGNOR TO FREDERICK DENHARD, OF BALTIMORE CITY, MARYLAND.

SAFETY DEVICE FOR ELEVATORS.

SPECIFICATION forming part of Letters Patent No. 687,186, dated November 26, 1901.

Application filed March 30, 1901. Serial No. 53,677. (No model.)

To all whom it may concern:

Be it known that I, URBAN S. ALZ, a citizen of the United States, and a resident of Gardenville, in the county of Baltimore and State of Maryland, have invented certain new and useful Improvements in Safety Devices for Elevators, of which the following is a specification.

The object of this invention is to provide 10 air-cushion devices for elevator-cars, so that in case of an accident to the hoisting and lowering mechanism a rapid descent of the car will be gradually checked at the bottom of the well or shaft, and thereby overcome a sudden 15 jar or stoppage.

A further object of the invention is to provide air-cushion devices of this character which can be conveniently applied to an elevator-car without any material alteration 20 thereof, and, furthermore, to so locate the said devices as not to interfere in any way with the proper operation of the car or occupy space which would prevent free use of the car and shaft.

With the above objects in view the invention 25 consists in locating in each of the four corners of the elevator-car a long tube or cylinder, closed at its upper end, and providing said cylinder with a piston having a cup-shaped washer adapted to compress the air 30 in the cylinder above said piston and form an air-cushion, the said piston carrying a rod or bar which depends below the cylinder and car to serve as a support for the latter.

The following specification enters into a detail description of my invention, reference 35 being had to the accompanying drawings and to letters of reference thereon, and what I claim in the particular construction of the air-cushion devices and their arrangement within 40 the car is more specifically set forth in the appended claims.

In the drawings forming a part hereof, Figure 1 is a view showing the application of 45 my invention to an elevator-car. Fig. 2 is a detail sectional view of one of the air-cushions. Fig. 3 is a detail sectional view of one of the pistons located in the tubes.

In carrying out my invention the ceiling 50 and floor of an elevator-car are cut away in the corners sufficiently to receive the ends of

tubes or long cylinders A, which extend the full height of the car and are firmly secured therein in any suitable manner. The upper ends of these cylinders are closed by means 55 of plugs B, which are preferably provided with flanges by which the upper end of the cylinder is secured to the top or ceiling of the car. It will be here noted that the said cylinders are located closely in the corners of 60 the car, and as they are comparatively small will occupy but very little space and their particular location will not reduce the capacity of the car.

In each cylinder A is located a piston C, 65 consisting of heads c c, between which is clamped a cup-shaped washer c', said washer being preferably made of leather of suitable thickness. The washer is dished upward, as shown, so that upon an upward movement 70 of the piston the air in the cylinder will be compressed above the same and pressing upon the projecting edges of said washer will force the same against the cylinder and form a tight piston. On the other hand, when said 75 piston descends the dished washer will contract and permit the air to pass into the cylinder around the same. The piston is therefore constructed similar to that of an ordinary bicycle-pump and is of particular advantage 80 in this application of the same, in that it will descend in the cylinder of its own weight and form a tight piston and effective air-cushion when forced upward.

To each piston C is connected a rod or bar 85 D, which extends therefrom through the bottom of the cylinder and is provided with collars d d', limiting its downward movement and also serving as an extra guide therefor, the collars having holes to allow the air to pass through 90 the same. It will be understood that the rod or bar D may pass loosely through an opening in the bottom of the cylinder, so that air will freely enter said cylinder; but I prefer to have the rod closely fit a central opening 95 and have air-inlet openings around the said central opening in order that the rod will then be properly guided at the lower end of the cylinder.

When the air-cushion devices hereinbefore described are applied to an elevator-car, as illustrated in Fig. 1 of the drawings, the

rods will depend below the car at the four corners thereof, and in the event the car should fall in the shaft the rods will strike upon the bottom of the shaft and, forcing the 5 pistons upward, the air will be compressed in the upper part of the cylinders and form an air-cushion which will receive the impact of the descending car. The devices will therefore insure a gradual stopping of the car at 10 the bottom of the shaft. In order that the rods may be properly centered, blocks E, having concave uppersurfaces, are located at the bottom of the shaft on a line with said rods.

The tubes or cylinders are carried within 15 the car and being very long will give a wide range of movement to the pistons, and it will be understood that the strength of these tubes or cylinders will be such as to withstand the pressure that will come upon the same in case 20 the car should drop from a considerable height. The bars D are braced by cross-bars f, slideable upon the aforesaid bars and supported thereon by chains f'.

The particular construction and arrangement of my improved air-cushion devices will 25 therefore not only provide a simple and effective means for arresting the rapid descent of a car in case of accident thereto, but also permit the said devices to be carried by the 30 car without decreasing its carrying capacity or otherwise mar the appearance or conveniences of the same.

Having thus described my invention, I 35 claim—

1. In a safety device for elevators, the combination with the elevator-car, of tubes or

long cylinders located in the corners thereof, pistons working in said cylinders, and rods secured to the pistons and depending therefrom through the lower ends of the cylinders, 40 substantially as shown and for the purpose set forth.

2. In a safety device for elevators, the combination with the elevator-car, of tubes or long cylinders located in the corners thereof 45 and extending from the ceiling to the floor, said cylinders being closed at their upper ends, pistons working in the cylinders and provided with cup-shaped washers dished upward, rods secured to the pistons and depending below the lower ends of the cylinders, and guides for said rods, substantially as shown and for the purpose set forth.

3. In a safety device for elevators, the combination with the elevator-car, of tubes or 55 long cylinders located in the corners of the car, plugs closing the upper ends of said cylinders, pistons with cup-shaped flexible washers working in said cylinders, rods attached to said pistons and projecting through the 60 lower ends of the cylinders, a collar on said rods, and blocks in the bottom of the shaft having concave surfaces adapted to receive the ends of the rods, substantially as shown and for the purpose set forth.

In testimony whereof I affix my signature in the presence of two witnesses.

URBAN S. ALZ.
